UNITED STATES PATENT OFFICE.

GUSTAV A. HARTER, OF CHICAGO, ILLINOIS.

BINDER.

1,261,523.

Specification of Letters Patent.

Patented Apr. 2, 1918.

Application filed January 28, 1916. Serial No. 74,734.

To all whom it may concern:

Be it known that I, GUSTAV A. HARTER, a citizen of the United States, residing at Chicago, in the county of Cook and State of Illinois, have invented certain new and useful Improvements in Binders, of which the following is a specification.

This invention relates to binders for sheets, pamphlets and the like, and the principal object of the invention is to provide a binder which will maintain the same thickness regardless of the number of sheets or pamphlets inserted therein.

The invention consists in the novel construction, combination and arrangement of the parts.

In the accompanying drawing, Figure 1 is a perspective of a binder constructed in accordance with the principles of this invention; Fig. 2 is a view looking at the end of the binder; Fig. 3 shows the construction of the preferred form of binder post; Fig. 4 is a top view of one of the fastening clips; Fig. 5 is a side view of the same, and Fig. 6 is an end view thereof.

Although this binder may be used for receiving perforated sheets and pamphlets, it is particularly designed and adapted to be used as a continuous reminder or advertising device for anyone who displays his wares or presents discounts, bulletins and the like in the form of sheets or thin pamphlets which would ordinarily become lost or would easily escape the attention of the person to whom they were sent unless placed in a conspicuous place. For example, if a thin pamphlet or catalogue is placed between a number of other or larger books or catalogues, the backs of the other catalogues may either overlap the thin one, or since the thin one has not sufficient back of its own upon which a designating mark can be placed it cannot be easily found and can be identified only by withdrawing it from between the other books. Many binders also have this objection; if a back is loosely hinged to covers, the back will not stand out even with the backs with other books when the binder is not full, but will soon take a position substantially parallel with one of the covers so that it is practically hidden and the back itself is invisible between the other books. By making the back and one of the covers rigid all of these objections can be overcome, and since the back is rigid with the cover it is held substantially at

right angles thereto, and by printing or otherwise designating the contents of the binder upon the back it can be readily seen will not be collapsed but will maintain the thickness of the back disclosed to view even though there be only a few sheets or pamphlets, or not any at all, in the binder.

In the present invention the binder comprises a back 7 with covers 8 and 9 hinged or otherwise connected thereto. The back and covers may be of any suitable construction, such as pressed board covered with paper or cloth, and printed on the outside, if desired, with any suitable designating or advertising matter to indicate the contents of the binder.

A plate 10 of sheet metal about as long as the binder is bent at substantially right angles and one of the angular portions is secured to one of the covers 9 and the other angular portion is secured to the inside of the back 7 binding its cover and the back rigidly at right angles to each other.

Before the angular strip 10 is secured to the back and cover a bar or a plurality of binder posts 11 are secured to that portion of the plate which will be secured to the cover 9, by riveting or otherwise fastening them thereto, and the upper extremity of each post is formed with a bent extremity 12 which extends toward the other angular portion of the metal strip 10 but is spaced a predetermined distance therefrom. Fastening clips 13 are pivoted on the angular portion of the strip 10 which is secured to the back 7 and each fastening clip is formed with an angular portion 14, a notch 15, and an angular extremity 16. The extremity 16 is yieldable so that when the clip is pressed down between the metal strip 10 and the extremity of one of the posts 11, the post striking the angular extremity 16 causes the clip to give slightly along the extremity 12 of the post to allow the latter to be seated in the groove 15, thus preventing the accidental disengagement of the clip with the post but allowing the clip to be easily raised from or pressed into engagement with the end of the post.

The metal strip 10 and the paper-holding or fastening means may be secured to the back and cover of the binder in any suitable manner. As shown in Fig. 1 they are rigidly secured together by rivets 17 and 18; the rivets 17 preferably forming the pivots about which the clips 13 are rotated into and

out of engagement with the posts 11. It will be observed that these clips overlap the posts slightly so that the overlapping portions may be easily grasped for raising or lowering the clips. When the clips are in position, as shown in Fig. 2, it is impossible to engage or disengage the sheets from the posts and the hinged cover 8 rests on the angular portion 14 of the fastening clips, thereby assisting in holding the clips in position, the clip also forming a partial rest for the hinged cover 8.

The insertion or removal of a perforated sheet or pamphlet from the binder will be readily understood from the above description. It is also obvious that the binder will not collapse even though there are no sheets whatever within it, but will always maintain the back at right angles to the cover 9 in any position in which it is placed.

By spacing the upper ends of the posts 11 from the back of the strip 10 the sizes of pamphlets which can be inserted in the binder can be limited as desired, preventing the insertion of larger ones.

What I claim is:

1. In a binder, a back and covers, an angular plate fixed to the back and one of the covers and holding them at right angles, binder posts secured to that portion of the plate to which the cover is attached, and members pivoted on that portion of the plate attached to the back having free ends rotatable parallel with the back to engage the upper ends of the posts.

2. A binder comprising a back and covers hinged thereto, of a rigid metal brace secured to one of the covers and the back for holding them in a fixed angular position with respect to each other, and binder posts fixed in the cover portion of the brace and bent over at the free ends toward but spaced from the back portion of the binder.

3. In a binder comprising a back and covers, the combination with an angular plate affixed to the back and one of the covers, of binder posts secured to the plate and substantially straight at their point of attachment but bent at the outer or free ends, and means in connection with the plate to yieldingly engage and cover the free ends of the posts.

4. In a binder, the combination with a back and covers therefor, one of the covers and the back being angularly fixed with respect to each other, and binder posts extending at right angles from said fixed cover and bent only at the upper ends toward the back, to limit the thickness of pamphlets to be held thereby.

5. In a binder of the class described, the combination of a back and covers one of which is angularly fixed with respect to the back, binder posts adjacent the

back extending upwardly from the angularly fixed cover, and members pivoted on the back and rotatable parallel therewith each adapted to yieldingly engage and cover the free extremity of one of the binder posts.

6. In a binder of the class described, the combination with a back and cover angularly fixed with respect to each other, binder posts rigidly attached thereto and extending upwardly from the cover each bent at its upper end toward the back, and a fastening clip for each binder post pivoted on the back having a resilient portion adapted to be pressed over the free extremity of the post and held in position by its resiliency.

7. In a binder of the class described, a back and a cover angularly fixed with respect to each other, binder posts extending upwardly from the cover and each bent at the upper end toward the back, and a fastening clip pivoted on the back having a resilient notch which is adapted to be pressed over the free end of the post to prevent engagement or disengagement of materials from the post.

8. In a binder of the class described, the combination with a metal angular member, of binder posts secured in one of the angular portions of the member and bent at their upper or free ends toward the other angular portion but spaced slightly therefrom, a fastening clip adapted to be pressed between the said other face of the angular portion of said member and the free end of each post, and a binder back and covers secured to the angular member.

9. In a binder comprising a back and covers one of which is angularly fixed with respect to the back, binder posts adjacent the back extending upwardly from the angularly fixed cover and bent at the upper ends so that the free extremities terminate a predetermined distance from the back, and fastening clips insertible between the back and the free end of each post to permit the engagement or disengagement of a material from the post.

10. In a binder of the class described, the combination with an angular member, of a post connected in one of the angular portions extending parallel to the other angular portion and bent at its upper end toward the said other portion, and a fastening clip pivoted to the said other angular portion having a resilient notched portion adapted to be pressed over the free end of the post to prevent accidental rotation of the clip in either direction with respect to the post.

11. A binder comprising a back and covers, a rigid metal strip angular in form and substantially as long as the binder, binder posts secured in one angular portion

of the strip and bent at their upper ends toward the other angular portion thereof but terminating a predetermined distance therefrom, fastening clips each having a 5 notched portion adapted to be inserted between the extremity of one of the posts and the angular portion of the metal strip from which it is spaced, and means for rigidly attaching the said metal strip to one of the 10 covers and to the back for holding them in a fixed angular position with respect to each other and for pivoting the fastening

clips on the metal strip, the other cover being held from engagement with the posts by engaging with the said clips. 15

In testimony whereof I have signed my name to this specification, in the presence of two subscribing witnesses, on this 24th day of January, A. D. 1916.

GUSTAV A. HARTER.
